LABEL FEED CONTROL

Walter J. Bernard, Oakland, Calif.

Application July 23, 1946, Serial No. 685,750

4 Claims. (Cl. 271—62)

1

This invention relates to accessible means for adjusting the feed of labels in a labeling machine.

Conventional labeling machines have means for adjusting the feed of labels, but the adjusting means is invariably located in a remote position on the machine, usually on the back of the machine while all other important adjustments are accessible from the front or operator's side of the machine.

Because of the remote location of the label feed control, many unnecessary shutdowns result because it is necessary for the operator to leave the front of the machine and terminate control while he goes to the back of the machine to make the adjustment.

Also, because of the remote location of this adjustment, and the loss of control of the machine while making the adjustment, labels are sometimes torn, applied on the bias to the containers, the containers pass through the machine without a label, and in consequence extended and frequent shutdowns occur, which does not solely involve the operator of the machine but probably a dozen or more additional workers who are operating along the labeling line.

My invention eliminates the above difficulties, failures, and shutdowns because it places the label feeding speed under continuous and instant control of the operator, easily accessible from the operator's position at the front of the machine, so that if feeding is not proceeding properly, the operator can instantly adjust the feed of the labels to suit the conditions. As is well known, labels vary in thickness due to the differences in thickness of coatings, even between labels in the same stack, for which reason, the feed may be perfect when a new stack of labels is started, and within a few seconds the label feed may be out of synchronism with the stream of containers, this because a stack of labels is used up in a minute or a little over. When the adjustment is under instant control, the label feeding speed can be adjusted instantly as may be necessary to compensate for the variations in thickness of portions of the stack of labels.

My invention is specifically designed for labeling machines of the general type disclosed in Patent No. 2,336,839, issued December 14, 1943, which has a turnbuckle with locknuts on the back of the machine for adjusting the label feed, and which cannot be reached from the operator's side of the machine, but is not limited to this specific type of machine, since minor modifications will readily adapt it to other machines.

2

The objects and advantages of the invention are as follows:

First, to provide a feed control which is directly and instantly accessible for adjustment from the operator's side of a labeling machine.

Second, to provide label feed adjusting means in an accessible position relative to the front of a labeling machine.

Third, to provide adjusting means which in itself is adjustable as to height to make it most convenient for control irrespective of the diameters of the containers being labeled.

Fourth, to provide a feed control adjustment which is easily substituted for the conventional adjusting mechanism.

Fifth, to provide a control which can be adjusted as to height to compensate for containers of different diameters to be labeled, and which is self-locking in any adjusted position, and to provide special locking means for securing the label feed control in any adjusted position.

In describing the invention reference will be made to the accompanying drawings, in which:

Fig. 1 is a side elevation of the invention shown partly in section to illustrate inner structures.

Fig. 2 is a bottom plan view of the ratchet or lock collar with a fragmentary view of the underside of the trip lever actuating arm.

Fig. 3 is a rear elevation of the invention shown to a reduced scale, as applied to a labeling machine of which only related parts are shown.

Fig. 4 is a side elevation of Fig. 3.

Fig. 5 is a fragmentary view showing on a moderately reduced scale showing the preferred method of connecting the trip lever arm to the trip lever by providing a direct connection.

The conventional labeling machine has a belt 10 depressed by spring-urged rollers 11 carried by suitable beams 12, for carrying the containers 13 through the machine at high speed, to apply siccative, pick up a label and roll it around the can and affix the follow end of the label, so that, in a continuous operation, the label is applied and sealed to the container. Because of the high speed of labeling, the labels 14 are used up rapidly, and must be advanced upwardly at a suitable speed so as to normally maintain the level above the top of the trip lever 15. So long as the top of the stack is above the trip lever, the bodies of the containers or cans ride on labels, but as the labels are picked up by succeeding cans the top of the stack is lowered to where the rims of the cans ride on and depress the trip lever, which through the conventional connection depresses the connection 16 with the spring 17 urging the pawl

lever 18 downwardly so that the cam 19 which is driven continuously will cooperate with the roller 20 and actuate the ratchet (not shown) to raise the stack of labels. Thus it will be realized that with thick labels the stack must be fed faster than the thin labels, and as the machine is operating on labels of one average thickness and the average thickness changes either in the same stack or in a new stack of labels, that the feed much be adjusted to suit.

With the conventional labeling machine, this adjustment is carried out by going to the back of the machine, loosening a couple of check nuts, then adjusting a turnbuckle and again tightening the check nuts. This is a delaying and slow procedure during which the operation of the machine may become entirely erratic with labels applied crooked, being torn, or with the cans passing through without labels.

My invention replaces the conventional turnbuckle and check nuts by a special adjusting shaft which extends above the top of the machine so that it can be reached and adjusted instantly at will, without loosening any check nuts or other locking devices, and also permits an instant feed at will irrespective of tripping of the feed lever, and is therefore devoid of the objectionable features of the conventional adjusting means, and almost entirely eliminates shutdowns. It increases production, and reduces costs.

The invention consists of a shaft 21 which is threaded at its lower end as indicated at 22 to fit the threaded end 23 of the pawl lever connection 16 on which the conventional turnbuckle is normally mounted, thereby replacing the turnbuckle and its locknuts.

This shaft has a collar 24 intermediate its height on which is rotatably supported a trip lever arm 25 to which the trip lever connection 26 is attached as indicated at 27, and the shaft is rotatable within the lever arm, and is secured against axial movement by a ratchet collar 28 which is fixed on the shaft as indicated at 29 and is provided in its undersurface with a circular series of indents 30 to cooperate with a ball-type pawl 31 which is urged by a spring 32 housed in a bore 33 in the arm 25.

An axially adjustable knob 34 is provided for the top of the shaft and includes a sleeve 35 of sufficient length to provide adjustment to any size of container passing through the machine, the larger the container, the higher will be the beam 12, and the purpose is to place the knob in the most convenient position, keeping it as low as possible while still readily accessible, and not to require adjustment from a position higher than is necessary at any time.

This sleeve has a slot 36 functioning as a keyway, and a pin 37 is fixed in the shaft to function as a key, to prevent relative rotation of the knob and shaft, while a ball 38 is urged by a spring 39 located in a bore 40 in the shaft to cooperate with a series of indents or apertures 41 to hold the shaft and knob in any relative axially adjusted position. When this knob is adjusted to its lowest position it is in the most conveniently accessible position from the front of the machine and will extend just above the beam 12 when the smallest containers are being labeled, and when in its most extended position with the lower end 42 of the slot cooperating with the pin 37, the knob will extend just above the beam when the largest containers are being labeled.

The preferred method of connecting the trip lever to the adjusting means is illustrated in Fig. 5. This method varies from the other method shown in that the connection is made direct between the trip lever and the holding or ratchet means with the connecting rod 26 omitted, thus eliminating one part, the holding means is identical to that illustrated in the other figures with the exception that a hole is bored transversely through the extension 25' instead of parallel with the axis of the shaft. This transverse hole receives the long pin 43 which replaces the conventional coupling pin 44. The collar 24 and clutch mechanism is so located on the shaft as to receive the pin as indicated in Fig. 5.

With this arrangement the shaft is rigidly held in an upright position—the pin forming a rigid support for the shaft with the clutch member or holding means simultaneously functioning as a bearing, and the pin with its trip lever providing a rigid support for the bearing. There are no nuts to work loose therefore there can be no wobbling of the shaft. The holding means being fixed against any rotative or swinging motion, adjustment of the shaft will be exact and not subject to any play as may be the case particularly if the securing nuts on the connecting rod 26 should work loose. Though that shown in Fig. 5 is the preferred type of connection there may be cases where a separate connecting rod will be required under which conditions a suitable connection such as the connecting rod 26 will be substituted.

For operation the knob is adjusted to the most convenient height. If it is seen that the labels are not feeding properly, the knob is adjusted from the normal operator's position until the feed is correct, the ball 31 holding the shaft in its adjusted position, adjustment taking place by rotating the knob to screw the threaded end 22 of the shaft down on the threaded end 23 of the pawl lever connection to decrease the speed of feed, and upwardly to increase the speed of feed of labels. This adjustment decreases or increases the total length of the connection between the trip lever and the pawl lever.

If prompt action is required to prevent damaging labels or the flow of non-labeled cans, a slight tap or push on the knob will result in an immediate feed of labels, thus taking care of emergency conditions. The adjustment being instantly accessible at all times the labeling machine can be kept operating at maximum speed and efficiency.

I claim:

1. In a labeling machine having a label feed control located at the rear of the machine and including a cam-actuable pawl lever having a pivot, and a trip lever actuable by containers being labeled, and a connecting rod having a combined pivotal and sliding connection at one end with said pivot on said pawl lever and threaded at the other end, and a spring for urging said connecting rod to its uppermost position on said pivot; adjusting means for said label feed control comprising a shaft having an axial threaded socket at its lower end threaded onto the threaded end of said connecting rod, with the upper end of said shaft extending above the level of the top of the machine for immediate access for tripping or rotative adjustment at will from the front of the machine; a trip lever arm having a bore with said shaft rotatable therein and having direct pivotal connection with said trip lever, and means for maintaining said trip lever arm against axial movement on said shaft, whereby manual de-

pression of said shaft will cause immediate actuation of said label feed, and rotative adjustment of said shaft will vary the length of the connection between the trip lever and the pawl lever to change the rate of feed, thus providing instant and continuous control of the label feed from the front of the machine.

2. A structure as defined in claim 1; a pair of spaced collars on said shaft for maintaining said trip lever arm against axial movement; said trip lever arm consisting of a collar having said bore formed axially therein and including means cooperative between said collar and said spaced collars for securing the shaft in its rotatably adjusted position and releasable through excess turning effort on the shaft for adjustment, and having an arm projecting from one side and terminating in an eye for said direct pivotal connection to said trip lever, whereby the number of parts is reduced to a minimum and the trip lever simultaneously functions as a support for the shaft.

3. A structure as defined in claim 1; a knob adjustable axially at will on the upper end of said shaft for adjusting the height relative to the level of the top of the machine for most convenient accessibility from the front of the machine, and including means maintaining said knob against rotation on said shaft.

4. A structure as defined in claim 1; a pair of 30

spaced collars on said shaft for maintaining said trip lever arm against axial movement; said trip lever arm consisting of a collar having said bore formed axially therein and including means cooperative between said collar and said spaced collars for securing the shaft in its rotatably adjusted position and releasable through excess turning effort on the shaft for adjustment, and having an arm projecting from one side and terminating in an eye for said direct pivotal connection to said trip lever; a knob adjustable axially at will on the upper end of said shaft for adjusting the height relative to the level of the top of the machine for most convenient accessibility, and means maintaining the knob against rotation on the shaft.
